UNITED STATES PATENT OFFICE.

GEORGE B. GRAF AND FLOYD E. WHITMAN, OF SHAWNEE, OKLAHOMA.

COMBINED LIQUID CONTAINER AND SPRAYER.

Application filed December 18, 1925, Serial No. 76,217. Renewed January 31, 1928.

Our invention relates to improvements in combined liquid containers and sprayers, and it consists in the combinations, constructions and arrangements herein described and 5 claimed.

An object of the invention is the provision of a device of simple construction which affords facilities for holding a liquid and has other means operable to cause liquid to 10 be drawn from the original container and discharged in an atomized state when desired.

A further object of the invention is the provision in a device of the character described of a novel arrangement of the cooperative portions of the liquid delivery tube and the air tube at one end of the container so that such cooperative portions of the air and liquid tubes of the device may serve as a 20 handle by means of which the device can be carried by hand from place to place.

A still further object of the invention is the provision of a device of the character described which is reliable in use, easy to 25 operate and thoroughly practical commercially.

Other objects and advantages of the invention will be apparent from the following description, considered in conjunction with 30 the accompanying drawings, in which

Figure 1 is a perspective view of a combined liquid container and sprayer embodying the invention,

Figure 2 is a central vertical section 35 through the device,

Figure 3 is a section substantially along the line 3—3 of Figure 2.

A practical embodiment of the invention as illustrated in the drawings includes a container which comprises a cylindrical body 1 which is shown as being disposed upright in Figures 1 and 2 and as being closed at its upper end by an upper end wall or top 2 and as being closed at its lower end by a lower 45 end wall or bottom 3. The top wall 2 of the container is provided with an inlet normally closed by the screw cap 4 so that the container may be filled with a suitable liquid which may have insecticidal or other desirable properties.

An air tube 4 extends completely through the body 1 of the container. As clearly shown in Figure 2, the rearward end portion of this air tube 4 is secured in a central opening 5 in the bottom wall 3 of the container, the joint between the lower end portion of

the air tube 4 and the wall of the opening 5 being airtight and the lower end of the air tube 4 preferably terminating flush with the lower face of the bottom wall 3 of the container. The portion of the air tube which extends through the body of the container is inclined from the vertical and is merged integrally or otherwise at its upper end into a vertical discharge end or nozzle portion 6 which extends upwardly from an opening 7 in the top wall 2 of the container, the opening 7 being located at the edge of the top wall 2 and the connection of the air tube with the wall of the opening 7 being such as to produce an airtight joint. The air tube decreases regularly in cross sectional area from the lower end of the portion 4 to the upper end of the nozzle portion 6 so that the velocity of air which is forced through the tube from its lower end will increase during the passage of the air blast through the tube.

The nozzle portion 6 of the air tube preferably is substantially rectangular in cross sectional contour as best seen in Figure 1 for a purpose which will be presently described.

A liquid delivery tube includes a portion 8 which depends through an opening 9 in the top 2 of the container into the space within the container and nearly to the bottom wall 3 of the container. The opening 9 in the top wall 2 of the container is diametrically opposite the opening 7. The portion 9 of the liquid delivery tube is bent above the top wall 2 of the container at 10 to extend at 11 horizontally above the top wall 2 of the container in the direction of the upper end of the air nozzle 6. The portion 9 of the liquid delivery tube increases regularly in cross sectional area from its lower end substantially to the level of the bend at 10 and then is uniform in cross sectional area throughout the portion at 11 which is merged at its outer end by a tapering portion 12 into a straight liquid discharge end portion or nozzle 13 which is shown as being uniform in cross sectional area throughout its length and as having a bore which is considerably smaller in cross sectional area than the bore of the remainder of the liquid delivery tube.

The outer end portions of the air nozzle 6 and the liquid nozzle 13 are connected and stayed rigidly to each other by a bracket which comprises a plate-like substantially

triangular body 14 which is disposed vertically edgewise and is formed with a tubular portion 15 at its upper edge through which the liquid discharge nozzle 13 extends 5 and to which the liquid discharge nozzle is secured in any suitable known manner, as by means of solder. The plate-like body 14 of the bracket also is formed with a vertically disposed tubular portion 16 which 10 forms in cross sectional contour to the upper end portion of the air nozzle 6 and through which the air nozzle 6 extends and to which the air nozzle 6 is secured rigidly, as by means of solder. The arrangement is such 15 that the adjacent ends of the tubular portions 15 and 16 of the bracket are spaced and the outer end of the liquid discharge nozzle 13 rests adjacent to its extremity on the upper end of the adjacent wall of the 20 air nozzle 6. Said adjacent wall of the air nozzle 6 is one of the longer or side walls of the rectangular nozzle and the liquid discharge nozzle 13 terminates slightly inward of the inner face of said adjacent side wall 25 of the air nozzle 6 so that a flat stream or blast of air may be discharged from the air nozzle 6 across the end of the liquid discharge nozzle 13 when the device is used in a manner which will be hereinafter 30 described.

It is to be observed at this point that the air nozzle 6, the brackets 14—15—16 and the portions 10, 11 and 13 of the liquid delivery tube may serve as a handle which can 35 be readily grasped and conveniently gripped in the hand so that the device can be carried readily from place to place when it is not in use.

The means for forcing air under pressure 40 through the air tube across the open discharge end of the liquid delivery tube may include an air displacing member which comprises a cylindrical body 17 and a lower head section or end wall 18. The cylindrical body 17 fits closely, although slidably, on the body 1 of the liquid container. The head 18 of the air displacing member is formed with an air intake opening 19 of 45 relatively great area centrally thereof. This air intake opening 19 is covered by a swingable inwardly opening flap valve 20.

From the foregoing description of the various parts of the device, the operation 50 thereof may be readily understood. The friction between the cylindrical portion 17 of the air displacing member and the cylindrical portion 1 of the container is such as to assure the retention of the air displacing member in place on the container 55 when the device is carried by hand in the manner hereinbefore mentioned. When desired, the device may be held in the hands of the user with the container body disposed horizontally or at any desirable inclination 60 to the horizontal. This can be conveniently 65

accomplished by grasping the portion of the liquid delivery tube that protrudes from the container in one hand while the air displacing member is grasped in the other hand. The air displacing member then is 70 moved rearwardly on the container body from the position shown in Figure 2. During this rearward movement of the air displacing member, air may pass through the opening 10 into the space between the head 18 of the air displacing member and the end wall 3 of the container. When the air displacing member is slid forwardly on the container body, the valve 20 will be closed 75 and air will be forced from the space between the head 18 of the air displacing member and the end wall 3 of the container through the air tube and will pass at high 80 velocity in a flat stream across the open end of the liquid discharge nozzle 13, it being understood that the device is held so that the open end of the discharge nozzle 13 will be turned upward. The suction resulting 85 from the passage of the air blast across the open end of the liquid discharge nozzle will cause liquid to be drawn from the container and to mingle in finely divided particles with the air blast, whereby the liquid will be atomized and discharged in a fine spray. 90 Since the inner end of the liquid delivery tube terminates close to the end wall 3 of the container and also close to the inner wall of the body of the container, it will be apparent that practically all the contents 95 of the container can be discharged therefrom in atomized form as a result of the operation of the air displacing member and the passage of the hereinbefore mentioned air blast across the open end of the liquid discharge nozzle 13. 100

Obviously, the invention is susceptible of embodiment in forms other than that which is illustrated in the accompanying drawings and described herein and we therefore consider as our own all such modifications and adaptations of the form of the device herein described as fairly fall within the scope of the appended claims. 105

We claim:—

1. A combined liquid container and sprayer comprising a container, a blow tube extending through said container beyond one end of the container, a liquid delivery tube protruding from the space within said container beyond said one end of the container in substantially spaced relation to said blow tube, the protruding portion of said liquid delivery tube being bent to terminate at the adjacent end of said blow tube, whereby an air blast may be delivered by said blow tube across the open outer end of the liquid delivery tube to draw liquid from the container through said liquid delivery tube and to atomize the liquid, and a bracket connecting the adjacent end portions of said 115 120 125 130 135

- blow tube and said liquid delivery tube, whereby said protruding portions of said blow tube and said liquid delivery tube and said bracket jointly constitute a handle 5 whereby said container may be carried.
2. A device of the character described comprising a container having a cylindrical body and end walls, an air tube connected at one end with a central opening in the end 10 wall of said container and extending through said container body and through an opening in the opposite end wall of the container, the connections of said air tube with the walls of said openings and the end walls of the 15 container being fluid tight, a liquid delivery tube protruding from said container, at the same end of the container as the protruding portion of the air tube and in substantially spaced relation to the latter, said protruding 20 portion of the liquid delivery tube being
- bent to terminate at its extremity in proximity to the adjacent end of the air tube so that a blast of air from the air tube will pass cross the open end of the liquid delivery tube, and a bracket connecting the adjacent 25 end portions of said tubes, said bracket comprising a plate-like body portion having tubular portions extending along adjacent edges thereof and respectively receiving end portions of said tubes, said tubular portion 30 of the bracket being secured to the portions of the air tube and the liquid delivery tube which extend through the tubular portion of the bracket and said bracket and the adjacent portions of said air tube and said 35 liquid delivery tube constituting a handle for the container, the inner edge of the bracket plate being concavely curved.
